UNITED STATES PATENT OFFICE.

WILLIAM M. HOWARD, OF BLACKVILLE, SOUTH CAROLINA, ASSIGNOR TO W. G. HOWARD
AND SONS, OF BLACKVILLE, SOUTH CAROLINA.

DEVICE FOR BABBITTING CONNECTING-RODS.

1,269,936.

Specification of Letters Patent. Patented June 18, 1918.

Application filed October 25, 1915. Serial No. 57,765.

To all whom it may concern:

Be it known that I, WILLIAM M. HOWARD, a citizen of the United States, residing at Blackville, in the county of Barnwell and State of South Carolina, have invented certain new and useful Improvements in Devices for Babbitting Connecting-Rods, of which the following is a specification.

This invention relates to a babbitting device and is especially designed to provide novel and improved means for babbitting the bearings of connecting rods used in connection with automobiles.

The main object of the present invention is to so provide simple, economical, efficient and unique means for molding the liner of Babbitt metal within the bearing of a connecting rod, that it may be readily and easily manipulated by unskilled labor, and at the same time serve as a time saving device over the old method employed for the purpose.

Another object of the invention is to provide a novel means for accurately and effectively securing the connecting rod in true position and alinement while being babbitted or lined.

A further object of this invention is to provide novel and improved means for forming a collar on the upper and lower portion of the Babbitt metal lining, said collar overlapping on the upper and lower surface of the bearing portion of the connecting rod.

The foregoing and such other objects as may appear from the ensuing description, are attained by the means hereinafter more fully described, and by the combination, construction, arrangement and location of the parts such as illustrated in the accompanying drawings and particularly set forth in the claims appended hereto.

Reference now being had to the accompanying drawings which form a part of this specification and in which similar numerals of reference indicate like parts throughout the several views, it will be seen that:

Figure 1, is a central longitudinal sectional view of the improved babbitting device embodying my invention, and showing the connecting rod in its babbitted position.

Fig. 2, is a plan view of the same, and

Fig. 3, is a view showing a side elevation of the device.

My improved babbitting device, as illustrated, comprises a base or support 1, which

consists of a metal plate or bar having at one end thereof an integral depending member 2, and at the other end is rigidly secured at right angles thereto a metal plate or bar 3, provided at each end with an integral depending member 4, said members 2 and 4 constituting feet or rests for supporting the device.

Resting upon one end of the base 1, surrounding a circular opening therein, is a washer 5 of any suitable metal provided with a recessed upper surface having an annular beveled portion 6, and a central bore 7.

The eye or bearing portion 8 of the connecting rod 8' to be babbitted is adapted to rest upon the upper surface of the washer 5, and a babbitting mandrel or core piece 9 is passed through the eye 8, said core piece having a body portion 10, reduced upper and lower portions 11, an upper threaded member 12, and a lower threaded member 13 which passes through the opening in the base plate 1, the body portion of the core piece resting upon the upper surface of the washer 5, and the lower reduced portion 11 within the central bore 7, and a nut 14 threaded on the member 13 for rigidly securing the washer 5 and said core piece to the base plate in a vertical position, as clearly shown in Fig. 1. Upon the upper surface of said eye 8, is placed a two piece washer 15, divided centrally, the lower portion being recessed and having an annular beveled portion 16, and a central opening 17, adapted to receive the upper reduced portion 11 of the said core piece 9, and formed on either side of the central portion of said washer 15 is an opening 18 to receive the babbitting metal which is poured in said openings 18. Upon the upper surface of the washer 15 is placed a washer 19, and a nut is adjusted to the threaded member 12 of the core piece adapted to firmly secure the washer 15 against the upper surface of the eye 8. Surrounding the said washer 15 is a split clamp 20 provided with a threaded bolt 21, and securing nut 22, for securely binding the two pieces of the washer 15 together, as clearly shown in Fig. 2.

The other end of the base plate 1 is slotted longitudinally, as at 23, to receive a threaded pin or bolt 24, which is adjustable laterally of the base plate to accommodate the length of the connecting rod, said threaded

105

110

bolt 24 having at each end thereof a securing nut 25 and 25', an intermediate adjusting nut 26, and intermediate loose collars 27 and 27' which are of conical shape to engage 5 within the eye 28 of the connecting rod 8', whereby by manipulating the securing nut 25 and the adjusting nut 26, the connecting rod is properly centered and secured in parallel alinement with the base plate.

10 It will be readily perceived that the core piece 9 is rigidly secured centrally within the eye piece 8 and forms an annular space with the inner walls of said eye piece and the washers 5 and 15, to receive the babbitt metal 29 which is poured in through openings 18, and forming a collar at both the upper and lower end of the Babbitt lining, said collars overlapping both the upper and lower surface of the said eye 15 piece, and in the event the pouring openings are filled to the top there will remain two cylindrical vertical extensions of the metal, such as shown at 30 and 31, which may be readily trimmed off.

20 25 The core piece 9 may be selected in accordance with the size of the shaft on which the connecting rod will be mounted, and since the connecting rod may be accurately adjusted and centered in proper alinement 30 the said core piece and washers 5 and 15 will reproduce an opening in exact accordance with the shaft to be used.

35 It is obvious that those skilled in the art may slightly vary the details of the construction and arrangement of the parts hereinbefore referred to without departing from the spirit of my invention.

Having thus described my invention what I claim and desire to secure by Letters Patent is:—

40 45 50 1. A babbittting device comprising a base plate, a piece to be babbitted, means mounted on said base plate for securing at one end said piece, said means consisting of a recessed washer having an annular beveled portion below said piece, a two piece recessed washer having an annular rim and provided with pouring holes therethrough above the piece, a core firmly secured upon the first named washer, and means carried by the base plate for supporting the free end of said piece.

55 60 2. A babbittting device comprising a base plate, a piece to be babbitted, means mounted on said base plate for securing at one end said piece, said means consisting of a recessed washer having an annular beveled portion below said piece, a two piece recessed washer having an annular rim and provided with pouring holes therethrough,

a clamp surrounding said two piece washer for firmly binding the pieces together, a core firmly secured upon the first named washer within the eye of the piece to be babbitted thereby forming a space to receive the Babbitt metal, and means carried by the base plate for securing the free end of said piece in proper alinement.

3. A babbittting device comprising a base plate, a piece to be babbitted, means mounted on said base plate for securing at one end said piece, said means consisting of a washer below said piece, a two piece washer above the piece, a clamp for firmly securing the two piece washer together, a core firmly secured upon the first named washer and having an enlarged body portion with reduced upper and lower portions and threaded at each end thereof, a securing nut threaded to each end of the core, and means carried by the base plate for securing the free end of said piece in proper alinement.

4. A babbittting device comprising a base plate, a piece to be babbitted, means mounted on said base plate for securing at one end said piece, said means consisting of a recessed washer provided with an annular beveled portion below said piece, a two piece recessed washer having an annular beveled portion, and pouring holes therethrough above the piece, a core passing through the piece to be babbitted firmly secured upon the first named washer and provided with an enlarged body portion, reduced upper and lower portions and threaded at each end thereof, a securing nut secured at each end of the core for securing all of the said parts to the base plate, and means carried by the base plate for securing the free end of the said piece in proper alinement.

5. A babbittting device comprising a base plate, a piece to be babbitted, means mounted on said base plate for securing at one end said piece, and means mounted on the other end of the base plate for accurately holding the free end of said piece in proper alinement, said means consisting of a vertically extending threaded bolt having a securing nut threaded to each end thereof, a pair of intermediate conical shaped loose collars adapted to secure and center the said free end, and an adjusting nut positioned between one of the said loose collars and the base plate.

In testimony whereof I affix my signature in the presence of two witnesses.

WILLIAM M. HOWARD.
